Primary Examiner — Patricia Palasik(74) *Attorney, Agent, or Firm* — Baker & Hostetler LLP**CLAIM**

I claim the ornamental design for an integrated motor assembly, as shown and described.

DESCRIPTION

FIG. 1 is a top perspective view of an integrated motor assembly according to a first embodiment of our new design;

FIG. 2 is a bottom perspective view thereof;

FIG. 3 is a top view thereof;

FIG. 4 is a side view thereof;

FIG. 5 is a rear side view thereof;

FIG. 6 is a front side view thereof;

FIG. 7 is a bottom view thereof; and,

FIG. 8 is a side view thereof.

Broken lines shown in the Figures represent unclaimed portions of the integrated motor assembly and form no part of the claimed design.
